Primary Examiner — Katherine A Holbrow*Assistant Examiner* — Riya Salil Kamat(74) *Attorney, Agent, or Firm* — IPTechLaw(57) **CLAIM**

The ornamental design for a shoulder exercise strap, as shown and described.

DESCRIPTION

FIG. 1 is a top, front perspective view of a shoulder exercise strap;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top, perspective view thereof being used for a shoulder exercise.

All broken lines in FIGS. 1-7 show portions of the shoulder exercise device that form no part of the claimed design. The broken lines in FIG. 8 show portions of the shoulder exercise device and environment that form no part of the claimed design.

1 Claim, 6 Drawing Sheets(56)
